MEDICINAL INFUSION FOR TREATING
GUMS

John A. McAlister, Jr., Takoma Park, D. C.

No Drawing. Application April 4, 1932
Serial No. 603,204

1 Claim. (Cl. 167—60)

This invention has for its object the provision of a liquid medicament to be used adjunctively to the known method of curing the tooth surfaces, and which promotes the restorative processes of the sloughed or shrunken tissues.

More specifically, the invention relates to infusion made from the leaves of the western highland or Rocky Mountain sage, *Artemesia*, variety *tridentata*, and perhaps other varieties.

10 Other objects of the invention will appear as the following description of a preferred and practical application of the same proceeds.

Referring now to a description of the invention in such detail as will enable those skilled in the art to practice the same, the infusion of sage is made by steeping a handful of sage leaves in a quart of boiling water until the liquid has attained an approximate mahogany color. If the infusion is to be used fresh, it is complete at this stage, but it may be preserved indefinitely by the addition of three to four ounces alcohol to a quart of the infusion. Sage leaves gathered in the month of May have been found to possess more potency in the performance of their function in the present medicament than leaves gathered at other seasons.

In the treatment of pyorrhea alveolaris, the tooth surfaces are carefully cured beneath the gingival margins and to the full depth of any pockets that may have developed, until the teeth are absolutely free from all adherent deposits which it is of course well known, are the foci of the inflammation which characterizes the disease. The spaces between the gingivæ and the tooth surfaces are then thoroughly flushed with the sage infusion, full strength, the same being introduced preferably from a spray bottle under the pres-

sure of compressed air. This cleanses the spaces and pockets from all trace of pus.

The sage infusion differs from other antiseptic medicaments such as iodin, inasmuch as the latter is corrosive in effect and leaves the tissues inflamed and exposed to re-infection, while the sage infusion on the contrary, is mollifying and therefore, regenerative in effect, favoring the natural restoration of sloughed and shrunken tissues so that the gums re-assume their normal condition, under treatment, and the teeth become tight.

After the application of the sage infusion, it is desirable to wash the mouth with an astringent such as a one to two percent solution of chromic acid, which has a marked reaction in the presence of the residual sage infusion in the mouth coagulating and segregating the debris of dead tissue in a manner more quickly and complete than in the absence of the sage infusion. After spitting out the chromic acid solution, the patient may employ any suitable mouth wash for the purpose of eliminating the taste of the previously applied solutions.

While I have in the above description disclosed what I believe to be a preferred and practical embodiment of my invention, it is to be understood that the strength of the infusion is not critical, and that such variations in the technique of applying the same may be employed, as experience in the use of the treatment may indicate as being desirable.

What I claim is:

Medicinal infusion for treating gums comprising an aqueous infusion of the leaves of western sage (*Artemesia tridentata*).
